UNITED STATES PATENT OFFICE

2,639,744

ADJUSTABLE CAM ACTUATED HOLD-DOWN CLAMP

William B. Herbert, Ridgewood, N. J.

Application March 7, 1951, Serial No. 214,395

2 Claims. (Cl. 144—290)

1

This invention relates to jig nuts and is an improvement over the construction embodied in my prior Patent 2,464,133, issued March 8, 1949, for Jig Nuts.

An object of this invention is to provide a jig nut construction embodying a pressure or clamping body with adjustable means whereby the clamping body may be placed under suitable clamping pressure to hold a work piece on a table or other suitable surface.

Another object of this invention is to provide a device of this kind which is so constructed and arranged that the degree of pressure to be applied to the work may be closely adjusted so that the same clamping pressure may be applied to similar work pieces as where mass production is being performed.

A further object of this invention is to provide a device of this kind which is simple in construction and can be applied to machine tool beds or other surfaces without changing the construction of the tool bed or surface.

A further object of this invention is to provide a device of this kind wherein the clamping body is formed with a socket or recess within which a pressure regulating washer engages, the socket holding the washer against shifting action caused by application of pressure to the work.

With the above and other objects in view, my invention consists in the arrangement, combination and details of construction disclosed in the drawings and specification, and then more particularly pointed out in the appended claims.

In the drawings,

Figure 1 is a detailed side elevation, partly broken away and in section, of a jig nut constructed according to an embodiment of this invention, showing the device in released position,

Figure 2 is a fragmentary sectional view taken on the line 2—2 of Figure 1,

Figure 3 is a fragmentary sectional view taken on the line 3—3 of Figure 2,

Figure 4 is a fragmentary sectional view taken on the line 4—4 of Figure 1,

Figure 5 is a fragmentary sectional view taken on the line 5—5 of either Figure 1 or Figure 4,

Figure 6 is a fragmentary sectional view taken on the line 6—6 of Figure 4,

Figure 7 is a fragmentary sectional view similar to Figure 3, but showing the device in clamping or operative position,

Figure 8 is a fragmentary sectional view of a modified form of this invention.

Referring to the drawings, the numeral 10 designates generally a machine tool bed which

2

has mounted on the upper side thereof a work piece 11. The bed 10 in the present instance is formed with an inverted T-shaped slot 13. The slot 13 has disposed therein a headed upstanding bolt 12, and a second bolt 14 is threaded into the bed or table 10 and is provided with an upper head 15.

A clamping body 16 engages on the upper end of the bolt 15 and bears at the opposite end 10 against the upper side of the work piece 11. The clamping body 16 is formed with an opening 17 through which the bolt 12 loosely engages, and a nut 18 is threaded on the bolt 12 and provides a means for initially exerting clamping pressure 15 on the clamping body 16.

The upper side of the body 16 is formed with a recess or socket 19 within which a washer 20 is adapted to loosely engage. A pair of cam studs 21 are rotatably mounted in openings 22 formed in the body 16, and the studs 21 are disposed in alignment and are secured to a lever 23. The openings 22 communicate with the socket 19 and each cam stud 21 is formed with a flat side 24 which is adapted to be disposed flush with the bottom of the socket 19 when the studs 21 are in released position.

In order to provide a means whereby the washer 20 may be adjusted within the socket 19 so that a selected clamping pressure may be applied to the clamping body 16, I have provided a pair of washer adjusting pins 25 which are disposed in sockets 26 formed in the body 16 and communicate with the socket 19. The pins 25 are constantly urged upwardly by means of springs 27, and the pins 25 are locked in adjusted position by means of set screws 28 which are threaded into the body 16. When the maximum clamping pressure is to be applied to the body 16, the upper ends of the pins 25 will be disposed flush with the bottom of the socket 19. In Figure 5 the pins 25 are disclosed in upwardly adjusted position so as to thereby hold the ring 20 above the bottom of the socket 19.

Referring now to Figure 8, the washer or ring 20a is adjusted within the socket 19a by means of one or more set screws 29 which are threaded vertically through the clamping bar 16.

In the use and operation of this device the headed bolt 12 is inserted in the T-slot 13 and the outer end of the body 16 is engaged on the fulcrum bolt 15. The inner end of the body 16 engages the upper side of the work piece 11 and the nut 18 is threaded downwardly on the bolt 12. The initial adjustment of the nut 18 may be 55 made by the hand of the operator and at this

time the lever 23 will be disposed in a vertical released position so that the flat sides 24 of the cam members 21 will be flush with the bottom of the socket 19. After initial hand adjustment of the nut 18, lever 23 may then be swung downwardly to a substantially horizontal position, thereby increasing the clamping pressure on body 16. In the event it is desired to place the work under less than maximum clamping pressure, the washer or ring 20 may be raised upwardly in the socket 19 by loosening the set screws 28 so that the spring-pressed pins 25 may move upwardly for the desired distance. When the pins 25 project upwardly into the socket 19, the cam studs or members 21 will apply a pressure to the body 16 which is less than the maximum clamping pressure.

I do not mean to confine myself to the exact details of construction herein disclosed, but claim all variations falling within the purview of the appended claims.

What I claim is:

1. A work clamping means comprising a tool bed having a T-slot therein a clamping body for engaging a workpiece on said tool bed, said body having a vertical bore between the ends thereof said bore terminating in an enlarged socket opening in the upper surface of said clamping body, an upright bolt loosely engaging through said bore, a head on said bolt engaged in said T-slot, a nut threaded on said bolt for adjusting said clamping body relative to said workpiece, a washer interposed between said nut and said body and located within each socket, a pair of aligned substantially cylindrical cam members 35 rotatably carried by said body and extending inwardly into said bore just below the bottom of said socket, each cam member having a flat face adapted to be disposed uppermost and confronting said washer when said cam members are in 40 released position, a lever fixed to said cam mem-

bers, and spring biased pin means carried by said body for adjusting said washer relative to said cam members.

2. A work clamping means comprising a tool bed having a T-slot therein a clamping body for engaging a work piece on said tool bed, said body having a vertical bore between the ends thereof, said bore terminating in an enlarged socket opening in the upper surface of said clamping body, an upright bolt loosely engaging through said bore, a head on said bolt engaged in said T-slot, a nut threaded on said bolt for adjusting said clamping body relative to said workpiece, a washer interposed between said nut and said body and located within each socket, a pair of aligned substantially cylindrical cam members rotatably carried by said body and extending inwardly into said bore just below the bottom of said socket, each cam member having a flat face adapted to be disposed uppermost and confronting said washer when said cam members are in released position, a lever fixed to said cam members, at least one spring pressed washer adjusting pin slidably carried by said body in confronting position with respect to said washer, and threaded locking means carried by said body for locking said pin in adjusted position.

WILLIAM B. HERBERT.
